(57) **CLAIM**

The ornamental design for a portable natural gas moisture analyzer, as shown and described.

DESCRIPTION

FIG. 1 is a front perspective view of a portable natural gas moisture analyzer according to the present invention.

FIG. 2 is a top view of the portable natural gas moisture analyzer of FIG. 1.

FIG. 3 is a front view of the portable natural gas moisture analyzer of FIG. 1.

FIG. 4 is a left side view of the portable natural gas moisture analyzer of FIG. 1; and,

FIG. 5 is a right side view of the portable natural gas moisture analyzer of FIG. 1.

The portable natural gas moisture analyzer includes a plain and unornamented back and bottom, which are not shown. Where applicable, elements are shown in broken lines herein for illustrative purposes only, and form no part of the claimed design.
